(57) **CLAIM**

The ornamental design for camera lens, as shown.

DESCRIPTION

FIG. 1 is a front view of camera lens showing our new design;

FIG. 2 is a left side view thereof;

FIG. 3 is a rear view thereof;

FIG. 4 is a right side view thereof;

FIG. 5 is a top plan view thereof;

FIG. 6 is a bottom plan view thereof; and,

FIG. 7 is a front perspective view thereof.

The broken lines which define the bounds of the claimed design form no part thereof.
